UNITED STATES PATENT OFFICE.

EARL P. SEDGWICK, OF NORTH CHICAGO, ILLINOIS, ASSIGNOR TO CHICAGO HARDWARE FOUNDRY COMPANY, OF CHICAGO, ILLINOIS, A CORPORATION OF ILLINOIS.

DESIGN FOR A TABLE STANDARD.

Application filed July 3, 1926. Serial No. 18,251. Term of patent 7 years.

To all whom it may concern:

Be it known that I, EARL P. SEDGWICK, a citizen of the United States of America, residing at North Chicago, in the county of Lake and State of Illinois, have invented a new, original, and ornamental Design for a Table Standard, of which the following is a specification, reference being had to the accompanying drawing, forming a part thereof.

The figure is a perspective view of a table standard showing my new design.

I claim:

The ornamental design for a table standard, as shown.

EARL P. SEDGWICK.
